UNITED STATES PATENT OFFICE

ALFRED PARTLOW, OF LINCOLN PARK, MICHIGAN, ASSIGNOR TO VORCLONE CORPORATION, OF MILWAUKEE, WISCONSIN, A CORPORATION OF DELAWARE

EXTRACTOR

Application filed March 31, 1928. Serial No. 268,408.

This invention relates to centrifugal extractors and particularly relates to the baskets of such extractors.

It is an object of the invention to provide one or more doors in the bottom of the basket of an extractor and to adapt the basket to be readily removed from the extractor curb, so that said door or doors may be opened to effect rapid discharge of the contents of the basket after such removal.

Another object is to provide an improved drive mechanism for the basket of an extractor permitting an easy and expeditious removal of the basket from the curb and its replacement therein.

Still another object is to provide an extractor basket with a pair of doors permitting a complete uncovering of the basket bottom, upon removal of the basket from the curb.

A still further object is to form the bottom of an extractor basket by a pair of hinged doors and to mount upon one of said doors a socket member for driving the basket and centrally supporting it within an extractor curb.

It is also an object of the invention to provide an improved means for latching in its closed position a door formed in the bottom of an extractor basket.

These and various other objects the invention attains by the construction hereinafter described and illustrated in the accompanying drawings, wherein:

Figure 1 is a view in exterior elevation of the improved extractor.

Figure 2 is a vertical sectional view of the same taken upon the line 2—2 of Figure 3.

Figure 3 is a top plan view of said extractor.

Figure 3^a is a detail sectional view of a joint formed between the doors of the basket in their closed positions, said section being taken on the line 3^a—3^a of Figure 3.

Figure 4 is a cross-sectional view taken through the central driving parts of the basket taken upon the line 4—4 of Figure 2.

Figure 5 is a view in elevation of the extractor basket showing its bottom-forming doors in open position.

Figure 6 is a fragmentary view in elevation of the latch means for the basket doors, the point of view being indicated by the line 6—6 of Figure 3.

Figure 7 is a cross-sectional view of said latch means taken upon the line 7—7 of Figure 6.

Figure 8 is a view showing in side elevation a driving member journaled upon the extractor curb, and sectionally showing a socket member upon the basket in detached relation to said driving member.

Figure 9 is a plan view of said driving member.

Figure 10 is a fragmentary horizontal, sectional view taken upon the line 10—10 of Figure 6 and further illustrating the latch mechanism for the doors of the basket.

In these views the reference character 1 designates the curb of an extractor, formed preferably of cast iron. For the purpose of this invention said curb may be mounted in any suitable manner, but it is preferred, for reasons hereinafter set forth, to suspend said curb by a plurality of bars 2 extending upwardly at a slightly outward inclination from the curb bottom and having their upper extremities respectively mounted in suitable posts 3.

As best appears in Figure 2, the engagement of said bars with said curb and posts is such as to afford the curb a slight lateral movement in any direction. In the curb bottom there is centrally formed an opening 4 through which freely passes a vertical drive shaft 5 provided beneath the curb with some suitable power transmission element, as for example, a sprocket wheel 6 engageable by a drive chain 6^a. Said shaft is journaled interiorly of the curb in a bearing member 7 secured to the curb bottom by bolts 8 or other suitable means. Said bearing member is exteriorly conically tapered and is interiorly provided with anti-friction bearing elements 9 mounting said shaft. The latter has a portion 10, projecting above the bearing member 7 and gradually tapered to provide a mounting for a driving member 11.

Said member preferably is formed with a skirt portion 12 which surrounds the bearing member 7, as clearly seen in Figure 2. The 100

upper portion of the driving member 11 is conically tapered at preferably an angle of approximately sixty degrees to the horizontal, and its skirt portion is tapered at a slight divergence to the vertical, substantially corresponding to the taper of the bearing member 7. Preferably an anti-friction thrust bearing 11^a is arranged between the top face of the bearing member 7 and the driving member 11. The latter is clamped upon the shaft 5 one or more nuts 13 engaging a stud 14 formed upon the upper end of said shaft.

Within the curb 1, in spaced relation to its side wall and bottom, is centrally mounted a basket 15 comprising the usual perforated circular wall formed of sheet metal or the like, exteriorly reinforced by hoops 16 and further interiorly reinforced by rings 17 and 18 riveted respectively to the top and bottom portions of said wall. The bottom of the basket is formed by a pair of substantially semi-circular doors 19 and 20, oppositely hinged to the ring 18 therebeneath as indicated at 21, and adapted in closed position to seat against said ring. The free edges of said doors are adapted to meet, in their closed position, in an approximately diametrical relation to the basket and preferably the door 20 is formed with a marginal lip 22 which overlaps a similar lip 23 on the door 19.

For rotatively mounting the basket 15 and establishing a drive thereto from the member 11, it is preferred to integrally form upon the door 19 a socket member 24, which in the closed position of the doors projects centrally upwardly within the basket and is adapted to fit snugly over the drive member 11, interiorly conforming to the latter. Thus the basket is entirely free to be lifted from the curb and out of driving engagement with the member 11 or to be lowered into such engagement, and the substantially conical form of said socket and driving members facilitates such engagement and disengagement. While the frictional contact between the parts 11 and 24, is under most circumstances adequate to transmit the desired drive, it is preferred to provide a number of spline ways 25 in the drive member 11 to receive splines 26 interiorly secured to the member 24 and preferably said spline ways and splines are of the wedge shape, best illustrated in Figure 8, so as to facilitate their mutual engagement and disengagement. It will be noted that the door 19 has a semi-circular projection 28 from its free edge to afford an adequate support for the socket member 24, (see Figure 3) the door 20 having a corresponding semi-circular opening at its free edge.

For locking the doors 19 and 20 in their closed positions, there is associated with each door a pair of latch mechanisms oppositely carried by the ring 18 and engageable with opposite points of the doors adjacent to the

free edges thereof. Each of these mechanisms comprises a latch bolt 29 radially slideable in the ring 18 and engageable in a socket 30 formed in a lip 31 marginally upstanding upon the corresponding door. A pin 31^a duplicating the bolt 29 is similarly slideable in the ring 18 above said bolt, said bolt and pin being rigidly connected by a coupling member 31^b and said ring having a chamber 32 opening in its inner face to accommodate said coupling member. A closure 33 for the chamber 32 is suitably secured to the inner face of the ring 18 and between said closure and the coupling member 31^b, springs 34 are coiled upon the pin 31^a and bolt 29 urging the latter to its locking position shown in full lines in Fig. 7. For retracting said bolt, a lever 35 is mounted in a circumferentially extending channel 36 in the exterior face of the ring 18 and is intermediately pivoted upon a pin 37 vertically secured in said ring. At one extremity, the lever 35 bears freely upon the outer end of the pin 31^a and is adapted to effect a retraction of said pin upon being shifted to the dash line position illustrated in Figure 10. To permit swinging of the pin-engaging end of said lever, the depth of that portion of the channel 36 which receives said end of the lever is increased as indicated at 38 in Figure 10. The other end portion of said channel is enlarged and increased in depth as indicated at 39 to permit the fingers to grip and operate the lever. Normally, said lever is retained in the channel 36 by the thrust transmitted to said lever through the pin 31^a from the springs 34. When said lever is swung to its dash line position, the pin 31^a, bolt 29, and yoke member 31^b are retracted as a unit, as is indicated in dash lines in Figure 7, whereby said bolt is withdrawn from the socket 30, permitting the corresponding door to drop. Thus the doors may be separately released, so as to permit a full or a partial opening of the bottom of the basket.

In the use of the described extractor, after completion of an extracting operation, the basket 15 is lifted out of the curb 1 by any suitable mechanism and conveyed to any point where it is desired to discharge the contents of said basket. At such point the latch mechanisms controlling the doors 19 and 20 are operated to release said doors, allowing them to drop to the open position shown in Figure 5, and thus permitting a free and unobstructed discharge of the contents of the basket. The doors are then again closed and latched, and the basket is replaced in the tub for further use.

An important feature of the construction is the provision made for very quickly removing the basket from and replacing it in the curb and establishing the driving connection during such replacement. This facility results primarily from the substantially conical form of the drive member 11 and of the co-

acting socket member 24, and also from the avoidance of any rigid connection between the basket and its drive member.

By adapting the curb 1 to undergo a slight 5 lateral movement in any direction, the extractor is permitted to yield slightly to the centrifugal force so as to diminish the strains upon its supports.

While the socket member in the disclosed 10 embodiment of the invention is illustrated as carried by one of the bottom-forming doors 19, 20, it is to be understood that the features of providing doors in the bottom of the basket to facilitate discharge of the basket and of 15 adapting the basket to be readily removed from the curb do not necessarily require use of one of said doors as a carrier for the driving and the supporting socket member.

Also, while it will be apparent that the 20 illustrated embodiment of my invention herein disclosed is well calculated to adequately fulfill the objects and advantages primarily stated it is to be understood that the invention is susceptible to variation, modification and 25 change within the spirit and scope of the subjoined claims.

What I claim is:

1. An extractor comprising a curb, a basket 30 rotatable in said curb formed with an opening at its bottom for discharging its contents and comprising a hinged closure for said opening, a bearing member centrally carried by the curb and rising therewithin, a shaft journaled in said bearing member, a driving member connected to said shaft above said bearing member and having a skirt portion surrounding said bearing member, and a socket member centrally carried by the basket therewithin, and adapted to be gravity-seated upon said driving member.

2. An extractor comprising a curb, a basket 45 normally rotatable within said curb, removable upwardly from the curb and having a bottom opening for discharge of its contents, and comprising a closure for said opening, a bearing member centrally carried by the curb and rising therewithin, a shaft journaled in said bearing member, a driving member engaged with said shaft above said bearing member and having a skirt portion surrounding said bearing member, said driving member having a portion of its exterior surface conically tapered, and a socket member carried by said basket for driven engagement 55 with said driving member and interiorly tapered to conform to the taper of said driving member, whereby said basket is freely upwardly removable from the curb to permit discharge of its contents through said bottom opening.

3. An extractor comprising a curb, a basket 60 rotatable in said curb, having an opening in its bottom for discharge of its contents, and comprising a hinged door controlling said opening, means normally holding said

door in closed position, a bearing member centrally secured to the curb bottom, rising within the curb, and having a conically tapered exterior face, a shaft journaled in said bearing member, a driving member connected to said shaft above said bearing member and formed with a skirt portion surrounding said bearing member and tapered to substantially conform to the bearing member, and having its upper portion conically tapered more 70 acutely than its skirt portion, and a socket member centrally carried by the basket, therewithin, and having differentially conically tapered portions adapting it to snugly embrace said driving member whereby said basket is freely removable upwardly from the curb, to permit discharge of its contents through said bottom opening.

4. An extractor comprising a curb, a basket 75 rotatable in said curb having an opening at its bottom for discharging its contents and having a closure for said opening formed with a socket member adapted to be positioned centrally within the basket in the closed position of said closure, means journaled upon said curb therewithin for interiorly engaging said socket member to support and drive the basket, and a shaft extending through the curb bottom for driving the last-named means.

5. An extractor comprising a curb, a basket 80 rotatable in said curb, having an opening in its bottom for the discharge of its contents, and comprising a hinged door normally closing said opening, said door carrying a socket member normally centrally located in the curb and opening downwardly, the socket of said member having a tapered portion, and a member journaled upon the curb therewithin tapered to fit within said socket to support and drive said basket, whereby the basket is freely removable upwardly from the curb.

6. An extractor comprising a curb, a basket 85 rotatable within said curb, having an opening at its bottom and comprising a pair of doors hinged at opposite points to said basket and meeting substantially diametrically of the basket, a driving member for the basket journaled upon the curb therewithin, and a socket member carried by one of said doors, and gravity-seated upon said driving member to support and drive the basket, whereby the basket is freely upwardly removable from the curb.

7. An extractor comprising a curb, a basket 90 rotatable in said curb, having an opening at its bottom for discharge of its contents, and comprising a pair of doors normally closing said opening, and hinged to said basket at opposite points thereof to swing downwardly, a drive member journaled upon the curb therewithin having an exterior conical taper, and a socket member carried by one of said doors and gravity-seated upon

- said drive member in the closed positions of said doors, whereby the basket member is freely upwardly removable from the curb to permit of opening of said doors.
8. An extractor comprising a curb, a basket rotatable in said curb having an opening at its bottom for discharge of its contents and comprising a pair of doors normally closing said opening and hinged to said basket at opposite points thereof, and meeting substantially diametrically of said basket, a bearing member centrally carried by the curb therewithin, a shaft journaled in said bearing member, a drive member mounted upon said shaft above said bearing member, and a socket member carried by one of said doors and adapted to seat by gravity upon said drive member in the closed positions of said doors.
9. An extractor comprising a curb, a basket rotatable in said curb, having an opening at its bottom for the discharge of its contents and comprising a pair of doors normally closing said opening and hinged upon said basket at opposite points thereof, a bearing member secured to said curb centrally therewithin, a shaft journaled in said bearing member, a drive member mounted upon said shaft and having a skirt surrounding said bearing member, and a socket member carried by one of said doors and adapted in the closed positions of said doors to seat by gravity upon said drive member.
10. An extractor basket having an opening at its bottom for the discharge of its contents and comprising a pair of doors hinged upon said basket at opposite points thereof and meeting substantially diametrically of the basket, a member carried by one of said doors for supporting and driving said basket, and means for normally holding said doors closed.
11. An extractor basket having an opening at its bottom for the discharge of its contents, and comprising a pair of doors hinged upon said basket at opposite points thereof, and meeting in their closed positions substantially diametrically of the basket, and a socket member carried by one of said doors and adapted to be positioned centrally within the basket in the closed positions of the doors for supporting and driving the basket, and means for normally holding said doors closed.
12. The combination with a cylindrical extractor basket having an opening at its bottom for the discharge of its contents, said basket comprising a door normally closing said opening and hinged to swing downwardly to uncover said opening, of a bolt carried by the basket and radially slidably to secure said door in its closed position, a spring urging said bolt to its effective position, and a lever exteriorly mounted upon the basket and controlling said bolt.
13. An extractor basket having an opening at its bottom for the discharge of its contents, and comprising a hinged door controlling said opening, means for normally holding said door closed and drive means for said basket carried by said door.
14. An extractor basket having an opening at its bottom for the discharge of its contents and comprising a pair of doors hinged upon said basket at opposite points thereof and meeting substantially diametrically of the basket, means for normally holding said doors closed and a member carried by one of said doors and disposed axially of the basket in the closed positions of the doors, said member providing a support and establishing a drive to the basket.
15. An extractor comprising a curb, a basket rotatable in said curb having an opening at its bottom for discharging its contents and comprising a closure for said opening, a drive element for said basket, means journaling said element centrally upon said curb and means carried by said closure for driving the basket from said element.
16. An extractor comprising a curb, a basket rotatable in said curb, having an opening at its bottom for discharging its contents, and having a closure for said opening, a bearing member centrally mounted upon the bottom of said curb, a drive member for the basket permanently journaled upon said bearing member, and means carried by said closure establishing a drive to the basket from said drive member and freely removable vertically from said drive member.
17. An extractor basket formed with an opening for the discharge of its contents, and comprising a closure for said opening movable to uncover said opening, means normally retaining said closure in its closed position, and drive means for said basket mounted upon said closure.
18. An extractor basket formed with an opening for the discharge of its contents, and comprising a closure for said opening movable to uncover said opening, means normally retaining said closure in its closed position, and a socket member mounted upon said closure and positioned in the closed position of said closure in a coaxial relation to the basket for supporting and driving the basket.
19. An extractor basket having an opening at its bottom for the discharge of its contents and comprising a pair of hinged doors meeting substantially diametrically of said basket, a member carried by one of said doors for supporting and driving the basket, and means for normally holding the doors closed.
20. An extractor comprising a curb, a basket rotatable in and upwardly removable from said curb, formed at its bottom with an opening for the discharge of its contents and provided with a closure for said opening, drive means for the basket, having an engage-

- ment with the basket, positively restraining said closure from opening movement while the basket is in the curb, and means for holding said closure closed independently of such driving engagement, said closure being adapted for movement to an open position when the basket is removed from the curb. 5
21. An extractor comprising a curb, a basket rotatable in and upwardly removable from said curb, formed at its bottom with an opening for the discharge of its contents and provided with a closure for said opening, hinged upon the basket to uncover said opening by a downward swinging, and a drive member for the basket within the curb positively restraining said closure from downward swinging, while the basket is in engagement with said member. 10
22. An extractor comprising a curb, a basket rotatable in and upwardly removable from said curb, formed at its bottom with an opening for the discharge of its contents and provided with a closure for said opening, hinged upon the basket to uncover said opening by a downward swinging, and coacting members upon the curb and basket, mounting the basket for rotation and positively restraining said closure from downward swinging, by their coaction. 15
23. An extractor comprising a curb, a basket rotatable in said curb, having a substantially flat bottom, a bearing member centrally carried by and rising within the curb, a shaft journaled in said bearing member, a basket-driving member connected to said shaft above said bearing member, and having a skirt portion in close proximity to and surrounding said bearing member, and an inverted socket member centrally carried by the basket therewithin, and seating on and centered by said driving member. 20
24. An extractor comprising a curb, a basket rotatable in said curb, having a substantially flat bottom, a bearing member centrally carried by and rising within the curb, a shaft journaled in said bearing member, a basket-driving member connected to said shaft above said bearing member, and having an exteriorly coned skirt portion surrounding said bearing member, in close proximity thereto, and an interiorly coned inverted socket member centrally carried by the basket therewithin, and having its coned face seating upon and centered by the coned face of said driving member. 25
25. An extractor comprising a curb, a basket normally rotatable in said curb and upwardly removable from the curb, having a substantially flat bottom, a bearing member carried by and rising within the curb, in a substantially coaxial relation therewith, a shaft journaled in said bearing member, a driving member engaged with said shaft above said bearing member and having a skirt portion surrounding and substantially con- 30
- forming to said bearing member, and means centrally carried by the basket mounting it upon said driving member in driven engagement therewith, and adapting it for free upward removal from the curb. 35
26. An extractor comprising a curb, a basket rotatable in said curb, a bearing member centrally secured to the curb bottom, rising within the curb, and having a conically tapered exterior face, a shaft journaled in said bearing member, a driving member connected to said shaft above said bearing member and formed with a skirt portion surrounding said bearing member and tapered to substantially conform to the bearing member, and having its upper portion conically tapered more acutely than its skirt portion, and a socket member centrally carried by the basket, therewithin, and having differentially conically tapered portions adapting it to snugly embrace said driving member. 40
